UNITED STATES PATENT OFFICE.

GEORGE H. STEELE, OF GLOVERSVILLE, NEW YORK, ASSIGNOR TO THE
HEACOCK MANUFACTURING COMPANY, OF SAME PLACE.

DESIGN FOR AN EGG-BEATER.

SPECIFICATION forming part of Design No. 26,438, dated December 22, 1896.

Application filed October 7, 1896. Serial No. 608,179. Term of patent 7 years.

To all whom it may concern:

Be it known that I, GEORGE H. STEELE, a citizen of the United States, residing at Gloversville, county of Fulton, and State of New York, have invented and produced a new and original Design for Egg-Beaters, of which the following is a specification, reference being had to the accompanying drawing, showing a view in perspective of an egg-beater embodying my design.

The egg-beater comprises the handle A, whip B, twisted stem or spindle C, disk D, and bosses D' and D''.

The handle is elongated and of general cylindrical form and surmounts the twisted stem or spindle C, which is of approximately the same length as the handle and extends therefrom to the boss D' on the upper side of the disk, the disk lying in a plane at right angles to the stem or spindle and between the boss D' on the upper side and the similar boss D'' on the lower side.

The whip comprises a frame B' upon the lower end of the spindle B'', the frame having a general elliptical form except at its lower end, where it is upwardly introverted to form a recess between two depending loops B'.

The leading feature of the design consists of the egg-beater comprising the disk lying between the two bosses, with the twisted stem 30 projecting upwardly from the upper boss and surmounted by the elongated handle, and the whip.

What I claim as new, and desire to secure by Letters Patent, is--

The design for an egg-beater herein shown and described.

In testimony whereof I have hereunto set my hand this 3d day of October, 1896.

GEORGE H. STEELE.
